UNITED STATES PATENT OFFICE.

RUDOLPH HOFFMAN, OF CHICAGO HEIGHTS, ILLINOIS, ASSIGNOR TO SEARS, ROEBUCK AND COMPANY, OF CHICAGO, ILLINOIS, A CORPORATION OF NEW YORK.

OVEN.

1,178,235.

Specification of Letters Patent.

Patented Apr. 4, 1916.

Application filed December 30, 1914. Serial No. 879,618.

To all whom it may concern:

Be it known that I, RUDOLPH HOFFMAN, a citizen of the United States, residing at Chicago Heights, in the county of Cook 5 and State of Illinois, have invented certain new and useful Improvements in Ovens, of which the following is a specification.

This invention relates to an improved 10 oven, and has for one of its objects the provision of a novel and improved joint or seal between the edges of the door and the oven wall to minimize the escape of heat.

Another object is to improve the construction of the door.

A further object is to provide improved means for connecting the door to the oven body and to limit swinging movement of the door.

20 In the accompanying drawings, Figure 1 is a front elevation of an oven embodying the features of my invention. Fig. 2 is a horizontal section taken in the plane of line 2-2 of Fig. 1. Fig. 3 is a vertical section 25 in the plane of line 3-3 of Fig. 1. Fig. 4 is a fragmental vertical sectional view taken in the plane of line 4-4 of Fig. 2. Fig. 5 is a fragmental front elevation of the upper left-hand corner of the oven, the door being 30 open and parts being broken away. Fig. 6 is a fragmental horizontal section on an enlarged scale taken in about the same plane as Fig. 2.

In the preferred form illustrated in the 35 drawings, the oven comprises two end walls 10 and a rear wall 11 secured together along their vertical edges by suitable seams 12. A top wall 13 has its edges curied to form beads 14 at its under side, the beads at the 40 ends and rear edge of said top wall fitting down over the end walls 10 and rear wall 11. The end walls have outturned flanges 15 at their upper edges which engage in the beads 14 to lock the top and end walls 45 together. The rear wall 11 has an in-turned flange 16 lying along the top wall 13. Corner-pieces 17 are mounted on the corners of the top wall and extend down beneath the beads 14 to give a finished appearance to 50 the corners. Said pieces are held in place by screws 18 engaging in the top wall, the two rear screws also passing through the flange 16 on the rear wall to secure said two walls together.

55 A front wall 19 closes the lower part of

the forward side of the oven, the upper part being closed by a door 20. At their forward edges the end walls 10 are provided with in-turned flanges 21. The front wall 19 is suitably secured to the lower portions of 60 these flanges, while the upper portions thereof of which extend along the door opening are of irregular shape, each flange extending from the end wall first inwardly, then rearwardly, then inwardly again, and being provided at its inner edge with a curl or bead 65 22. Between said bead and the rearwardly extending portion of the flange is formed a groove 23 and the vertical edge of the door is provided with a flange 24 to pass into 70 said groove and be tightly confined therein. Since the flange is made of sheet metal, it may, if desired, be made to yield so as to form a tight joint or seal with the flange on the door.

75 A member 25 of substantially the same shape as the flanges 21 extends horizontally beneath the forward edge of the top wall 13 and above the door 20. Said member is provided with a bead 26 at its lower edge 80 which forms a groove 27 to receive a flange 28 on the upper edge of the door. Angle pieces 29 are fitted into the beads 22 and 26 at both the upper corners of the oven, the member 25 being supported by said angle 85 pieces. The member 25 may also be suitably secured to the end walls 10. The door is provided with a rotatable latch or clip 30 adapted to engage the member 25 to hold the door closed, said clip having a handle 31 90 fixed with relation thereto.

The door 20 comprises a suitable frame which surrounds and supports a central panel 32. The panel may consist of a pane of glass having a metallic rim or binding 95 32^a at its edges. The frame provides a stop shoulder 32^b against which the panel abuts, the panel being inserted into the frame from the rear side thereof. A suitable number of transverse wires 32^c pass 100 through parts of the frame and lie behind and close to the panel 32 to hold the latter in place. These wires may be slid longitudinally in their openings in the frame to disengage one or both ends of the wires and thus permit of removing the glass panel and substituting a solid metal panel if desired. The door is hinged at its lower edge to the body of the oven by means of pairs of hinge members. In their pre- 110

ferred form each pair of hinges comprises an upper member 33 secured to the door and having at its lower end oppositely projecting lugs 34 forming pintles, and a lower member 35 secured to the body of the oven by bolts 36 and having at its upper edge a pair of curled lugs 37 forming bearings which inclose the pintles 34, said bearings being open at their rear side to permit the introduction and withdrawal of the pintles 34 when the bolts 36 are loosened and the lower member drawn forwardly. Arms 38 on the upper hinge members pass through slots in the front flanges 21 of the end walls, 15 said arms being arranged to abut against stop projections 39 on the end walls when the door is swung downward, so as to support the door in a horizontal position. When closed the lower edge of the door is 20 tightly held against the front wall 19.

The lower edges of the end walls 10, rear wall 11 and front wall 19 are turned in toward each other to form flanges 40. A false bottom wall 41 has fixed beneath opposite ends a pair of downwardly extending flanges 42 which rest at their lower edges upon the flanges 40. The rear edge of the bottom wall 41 fits snugly between the end walls 10, but the forward portions 25 of the ends of the bottom wall are bent upwardly, as at 43, to permit the swinging movement of the stop arms 38. The bottom wall 41 is provided with a plurality of openings 44 therethrough adjacent to its 30 edges. To the lower face of the bottom wall is secured a semi-cylindrical plate 45 which acts to direct the heated air through the openings 44 into the oven.

A set of inner or lining walls are located 40 in spaced relation to the outer walls heretofore described, the said inner walls consisting of an upper wall 46 having upturned flanges 47, which abut against the top wall 13, the flanges at the rear edge and ends 45 lying alongside the rear wall 11 and end walls 10.

The rear lining wall 48 abuts at its ends against the end walls 10, at its upper edge against the top lining wall 46, and at its 50 lower edge against the false bottom wall 41, and is provided with rearwardly extending flanges 49 abutting against the rear wall 11.

Each of the end lining walls 50 abuts at its edges against the top and rear lining walls and false bottom wall, and each is provided at its upper and rear edges with laterally extending flanges 51 which abut against the outer end wall, and at its lower edge with a flange 52 which abuts against 55 the flange 43 on the bottom 41. At its forward edge each end wall is provided with a flange 53 which lies along the flange 21 on the end wall, the said flange 53 being turned out at its edge to engage the shoulder formed 60 by the bead which makes the groove 23.

One or more ledges 54 are secured to the inner faces of the inner end walls 50 for slidably supporting grids 55.

The inner walls 41, 46, 48 and 50 do not require any fastening devices, the top wall 70 being supported by the rear and end walls, the rear wall being held in place by the end walls, and the said end walls being prevented from inward movement by the grids 55. These walls, therefore, may be very quickly 75 assembled and are securely held against displacement without fastening devices.

In assembling, the false bottom wall is first put in place, then the top lining wall 46, then the rear wall 48, and the forward 80 edges of the end walls 50 are then engaged with the flanges 21 and said end walls are pushed into place. The grids are now put on their ledges.

I claim as my invention:

1. In an oven, the combination of a body having a door-opening, and having sheet metal members at the edges of said opening, said members having curled beads at their inner edges and being folded to form 90 grooves adjacent to said beads, said grooves having three walls, and a door having angular flanges at its edges adapted to enter said grooves when the door is closed.

2. In an oven, the combination of a body 95 having a door-opening and having sheet metal members at the edges of said opening, said members having their inner edges curled to form beads and the members having a rearwardly bent portion forming with 100 said beads longitudinal grooves having three walls, and a door having rearwardly extending angular flanges adapted to enter said grooves when the door is closed.

3. An oven comprising two sides and a 105 top, irregularly shaped flanges extending inwardly from the forward edges of said sides, a member depending from the forward edge of said top, said flanges and said member each having a rearwardly bent portion and 110 having a curl or bead at their inner edges to provide grooves having three walls, and a door hinged at its lower edge and having rearwardly extending angular flanges at its 115 vertical edges and its upper edge, the flanges being adapted to enter said grooves when the door is closed.

4. An oven comprising a body having a door-opening and having sheet metal members at the edges of said opening, each of 120 said members having its inner edge curled and being bent to form with said curled edge a three-walled groove, and a door having angular flanges adapted to overlap said curled edges and enter said groove when the 125 door is closed.

5. In an oven, a door comprising a sheet metal frame providing a central opening and having a stop shoulder located at the edge of and projecting into said opening, a 130

panel having its edges fitting within the opening and abutting against said shoulder, and a plurality of transverse wires having their ends removably seated in said frame, 5 said wires lying closely alongside said panel and constituting the means for holding the latter in place.

6. In an oven, in combination, a body comprising a front wall and two end walls, 10 a door, two pairs of hinges connecting the lower edge of the door to said front wall, the hinged members secured to the door consisting of flat plates separate from but rigidly secured to the forward face of the 15 door, each plate having one edge bent at

right angles to the plate and extended to provide a stop arm which passes to the interior of the oven and lies closely alongside the end wall of the oven, and two stops rigidly mounted in the respective end walls 20 and each adapted to have one of said arms abut against it for limiting the opening movement of the oven door.

In testimony whereof, I hereunto set my hand in the presence of two witnesses.

RUDOLPH HOFFMAN.

In the presence of—

GEORGE L. CHINDAHL,
MARGARET H. MANN.
